UNITED STATES PATENT OFFICE.

ROBERT FLOYD SALISBURY, OF NEW KENSINGTON, PENNSYLVANIA, ASSIGNOR TO
ALUMINUM COMPANY OF AMERICA, OF PITTSBURGH, PENNSYLVANIA, A COR-
PORATION OF PENNSYLVANIA.

POLISHING MACHINE.

Application filed May 4, 1922. Serial No. 558,345.

To all whom it may concern:

Be it known that I, ROBERT F. SALISBURY, a citizen of the United States, and a resident of New Kensington, in the county of Westmoreland and State of Pennsylvania, have invented a new and useful Improvement in Polishing Machines, of which the following is a specification.

This invention relates to a buffing or polishing machine for holding articles and presenting the same to a buffing wheel, and it is especially designed for polishing metal articles such as cooking utensils or other objects of a similar character.

The principal object of the invention is to provide a simple, compact, and efficient machine for the purpose set forth which is constantly under the control of the operator who by manipulating control levers provided for the purpose can shift the several parts comprising the apparatus to cause all portions of a straight, tapered, curved, or irregular surface to be properly brought into contact with the polishing or buffing wheel with which it is used.

A special object is to provide an apparatus in which the article operated upon may be shifted longitudinally, transversely, or angularly of the axis of the polishing wheel, in which the shifting in the several directions mentioned may be effected either independently or conjointly, and in which the tension or pressure between the article operated upon and the buffing wheel is at all times directly responsive to the touch of the operative.

It is also an object to provide an apparatus in which the tension or pressure between the polishing wheel and article is not affected by special springs, the weight of the parts, or other mechanical expedients of a similar nature, but is entirely independent of such devices, being varied directly in response to the force exerted by the operative upon hand gripped members for shifting the several parts.

Still further objects are to provide an angularly adjustable gear housing for the work carrying spindle mounted upon a transversely shiftable saddle so as to enable articles of conical or frusto-conical form to be more readily polished, and to provide means for preventing relative rotation of the work

carrying spindle when the driving gearing is disconnected therefrom.

It is also a special object to provide an apparatus in which the work holding device and the means for actuating it are so related to the buffing wheel that articles having curved surfaces may be more readily polished than has been possible with known devices for such purposes.

These and other objects of the invention will more readily appear when taken in connection with the following description and the appended claims.

In the accompanying drawings Fig. 1 is an end elevational view of the preferred embodiment of the invention; Fig. 2 a vertical sectional view with parts in elevation of the apparatus illustrated in Fig. 1; Fig. 3 a diagrammatic view illustrating the relative positioning of the main carriage or slide and the work supporting means with relation to the buffing wheel; Fig. 4 a fragmentary sectional view illustrating the clutch shifting mechanism employed, said section being taken on line IV-IV of Fig. 2; Fig. 5 a view similar to Fig. 4 taken in the same plane but looking in the direction of the arrows V-V, illustrating the means employed for preventing rotation of the work carrying spindle when the clutch is disconnected from the driving gearing; Fig. 6 a sectional plan view taken on line VI-VI, of Fig. 2; Fig. 7 a fragmentary detail sectional view illustrating the mechanism employed for shifting the transversely movable saddle; and Fig. 8 a detail view illustrating the method of mounting the actuating lever and its associated parts of the mechanism shown in Fig. 7.

In the embodiment illustrated in the drawings, 1 designates a base plate adapted to be secured to the floor in any suitable manner, as by bolting, provided with lateral guiding grooves 2, 2' in which the heads 3 of bolts 4 passing through openings in the flange 5 of the pedestal 6 slide for the purpose of adjustably fixing the pedestal at any desired distance from the buffing or polishing wheel W. This adjustment is effected in an obvious manner by loosening the nuts 7, moving the pedestal to the desired location, and subsequently tightening the said nuts to bind the flange 5 to the base

plate 1. The buffing wheel W, shown in dotted lines upon the drawings, is of any suitable character for the purpose intended, being rotated in the usual manner by an actuating apparatus, the end portion of which is indicated at L.

The details of construction of the wheel W and apparatus L do not affect the present invention, but the relative positioning of the same with relation to the work holding machine is highly important, for a purpose to be presently described, and for that reason the pedestal is mounted so that the axis of the turn table rotatably mounted thereon is always in the same vertical plane as the wheel W as clearly shown in Figs. 2 and 6, and this is true regardless of the distance at which the pedestal is positioned from the said wheel.

The pedestal 6 is provided adjacent its lower end with a spider 8 having the bearing boss 9, and at its upper end with an internal flange 10 for supporting a roller bearing 11. Journalled in the bearing 11 is a sleeve 12 telescopically fitting within a boss 13 depending from a turn table 14, and fitting within the sleeve 12 is the upper end of a shaft 15, the lower end of which is journalled in the bearing boss 9, sleeve 12, boss 13, and shaft 15 being rigidly secured together by means of a pin 16 passing through the several parts. The lower portion of the boss 13 is enlarged and contains a recess into which an annular flange 17 formed on the pedestal projects. The diameter of the extreme lower end of the boss 13 corresponds to that of the upper end of the pedestal and it is employed as a braking surface coacting with the inner surface of a split clamping ring 18 which is attached to the pedestal by means of bolts 19 extending through an ear 20 formed upon the ring. One of the ends 21 of the ring 18 is threaded for the reception of a clamping screw bolt 22 adapted to draw the ends of the ring together and engage the braking surface of the boss 13 whenever it is desirable to lock the turn table and pedestal against relative movement, and in order to more readily actuate the bolt 22 the same is equipped with a comparatively long actuating bar 23.

The upper surface of the turn table 14 has formed thereon an integral guiding dovetail rib 24 upon which a cooperating carriage or slide 25 is mounted for reciprocating sliding movement, and for facilitating assemblage of these parts a gib indicated at 26 is used. A rack bar 27 is fixed to the bottom surface of the carriage or slide 25 extending longitudinally along its centre and meshing with this rack is a spiral pinion or worm 28 attached to the inner end of an operating shaft 29 extending at an angle to the axis of the slide 25, and suitably journalled upon

the turn table, said shaft being provided with a hand wheel 30 at its outer extremity. Rotation of the wheel 30 causes the slide 25 to reciprocate upon the turn table in an obvious manner, its direction of movement depending upon the direction in which the wheel 30 is rotated, and in order to limit the extent of movement of the slide any suitable stops may be employed. Attached to one end of the slide 25 is a guard 31 which is adapted to cover and protect the upper surface of the turn table whenever the slide is moved towards its right, as viewed in Fig. 2. The opposite end of the slide is provided with an integrally formed dovetail guiding rib 32 which extends transversely to the axis of the slide, preferably at right angles thereto. This rib is similar to the rib 24 and has slidably mounted thereon for reciprocating movement a saddle 33 which in turn carries an angularly adjustable gear housing 34. The housing 34 is pivotally mounted by means of an apertured boss 35 formed on its base which fits an aperture 36 in the saddle, and the two are held in operative relation by a bolt 37 having a bar 38 and nut 39 threaded upon its lower and upper ends respectively, the bar 38 being prevented from turning by the lug 40 projecting from the bottom face of the saddle. In order to furnish access to the several parts the housing 34 is provided with an opening 41 at one side. After the housing has been adjusted to the desired angular position by turning about its pivotal support, the same may be locked in its adjusted position by bolts 42 threaded into the body of the saddle and extending through arcuate slots 43 in the base flange 44 of the housing, as clearly shown in Fig. 6.

The saddle 33 is adapted to be reciprocated by an operating lever 45 of special construction pivoted loosely upon a rocker shaft 46 fitting within and supported by a pair of spaced apertured lugs 47 and 48 formed integrally with and extending from one side of the slide 25. The operating lever 45 consists of a hollow barrel 49 closed at its outer end by a cap 50 and fixed at its inner end is a collar 51 provided with two spaced apertured lugs 52 through which the shaft 46 extends, the collar 51 being split at 53 and adapted to be clamped to the barrel 49 by means of a bolt 54. Located within the barrel 49 is a plunger 55 provided with a nose 56 adapted to engage any one of a series of notches 57 of a ratchet 58 keyed to the shaft 46 and disposed between the lugs 52. The plunger is normally urged into engagement with the ratchet by means of a coiled compression spring 59 disposed between the outer end thereof and the cap 50. For retracting the nose 56 so as to position it in the desired notch 57 an actuating ring 60 is provided,

which surrounds the barrel 49 and is slideable thereon. The ring is connected to the plunger by a pin 61 extending through elongated slots 62 disposed at opposite sides of the barrel 49. Keyed to the shaft 46 adjacent the left hand lug 52, as viewed in Fig. 8, is an arm 63 having a series of apertures 64 in which one end of a link 65 is pivotally connected as indicated at 66, the opposite end of the link being pivoted at 67 to a lug 68 depending from the bottom face of the saddle 33. By selecting the proper aperture 64 in which to pivot the link 65 and the proper notch 57, the lever 15 45 may be adjusted to suit the needs of various operatives and characters of work. It is noted that the saddle 33 and the parts carried thereby are reciprocated transversely of the slide 25 upon the guiding rib 32 solely by the force exerted through the lever 45 by the operative, and are under his control and influence at all times. In this way the pressure or tension exerted between the article treated and the polishing wheel is constantly under the will of the operative, as will more fully appear as the description proceeds. This feature is of great practical importance since it eliminates the effect of all mechanical devices, such as springs, weight of the parts, etc., commonly employed, and renders the control highly sensitive to the touch of the operative.

Journalled in the bushings 70 and 71 fixed in suitable bosses disposed at opposite sides of the housing 34 is a work holding spindle 72, the inner end 73 of which is threaded to receive the attaching hub 74 of a mandrel block, not shown, for supporting the article to be polished. The inner portion of the spindle is tapered, as clearly shown in Fig. 2, and is held in position by means of nuts 75 at its outer end. Fixed to the intermediate portion of the spindle within the housing is a bushing 76 upon which is journalled a sleeve 77. Keyed to the sleeve 77 so as to rotate therewith is a bevel gear 78 meshing with a bevel gear 79 attached to the lower end of a vertical shaft 80, suitably journalled in an extension 81 projecting upwardly from the gear housing, said vertical shaft being connected through the universal joint 82 with overhead driving mechanism, as is usual in machines of this character. Mounted for sliding movement upon the intermediate portion of spindle 72 by means of feathers 83, 83' is a clutch collar 84 provided with teeth 85 and 86 at its opposite sides. Teeth 85 cooperate with similar teeth 87 formed on the face of sleeve 77 while the tooth or lug 86 is adapted to abut the extremities 89 and 90 of the semi-circular flange 91 projecting inwardly from the housing 34 and surrounding the spindle 72. Whenever the teeth 85 engage the teeth on sleeve 77, motion is transmitted from the shaft 80 to the work holding spindle 72 to rotate the same, and when the clutch is moved towards the right, as viewed in Fig. 2, sufficiently far to cause lug 86 to engage the flange 91, said spindle is locked against turning movement in either direction. This enables mandrel blocks to be applied to or removed from the spindle without danger of turning movement during such operation.

In order to slide the clutch member 84 upon the spindle, an actuating lever 92 projecting through an opening 93 in the housing 34 is employed, this lever forming a part of a yoke 94 pivoted at 95 and connected by a pair of trunnions 96, 96' to an annulus 97 fitting within a peripheral groove in the clutch collar.

A downwardly inclining partition 98 extends across the interior of the housing 34 below the spindle and its associated gearing forming a closed bottom so that lubricant may be retained therein. The lubricant is fed to the housing through a suitable inlet, not shown, located in its top. Due to the inclination of the partition 98, sediment and foreign particles settling thereon find their way to the trough 99 at its lower edge and may be removed through the drain opening 100 normally closed by a threaded plug 101.

Bolted to one side of the top of the gear housing 34 is a bracket 102 having the upwardly extending arms 103 and 104. The upper end of the arm 103 forms a portion of a clamp 106, the other portion of which is in the form of a removable clamping jaw bolted thereto as indicated at 107. This clamp is adapted to grip and hold a supporting rod 108 the threaded right hand extremity of which, as viewed in Fig. 2, extends through a boss 109 on arm 104, and is engaged by an adjusting wing nut 110 for moving the rod longitudinally of the machine. The opposite end of the rod 108 carries a collar 111 provided with a locking rib 112 for cooperating with a groove 113 in the face of a sleeve 114 carrying the back block supporting arm 115. Sleeve 114 is freely rotatable upon the rod 108 and is normally urged into contact with the collar 111 by a coiled compression spring 116 whose tension may be varied by adjusting the nut 117 threaded upon the extremity of the rod, a lock nut 118 being also provided.

The extremity of the arm 115 is equipped with a bearing 119 in which a short stub shaft 120 is journalled, carrying a head 121 on which the usual back block, not shown, is mounted, the article treated being supported between the back block and the mandrel attached to the operating spindle in a well known manner. The parts are so arranged that when the same are in their operative positions as shown in Fig. 2, the shaft 120 and spindle 72 are in alignment. In order to swing the arm 115 to its inoperative posi-

tion to remove a finished article and replace it by another to be treated, it is merely necessary to press the arm against the spring 116 sufficiently to effect disengagement of the rib 112 and groove 113, after which the arm may be freely rotated around the rod 108 as an axis to any desired angle.

When the machine is installed the pedestal 6 is adjusted upon the base plate 1 to the most desirable distance from the wheel W, according to the character of the work, and is readjusted only as changes in the character of the work demand. The distance between the work supporting mandrel and the back block attached to the head 21 is also adjusted to accommodate the articles being treated.

In operation, power is constantly applied through the over-head driving mechanism, previously mentioned, to the shaft 80 which causes rotation of gear 78 and sleeve 77 through gear 79. By throwing the clutch 84 into or out of engagement with the sleeve 77 by means of lever 92 the work holding spindle 72 may be rotated at will. After the spindle 72 has been put into rotation, the article supported upon the mandrel may be moved to any desired position within the limits of the machine by rotating the hand wheel 30 to reciprocate the slide of carriage 25 longitudinally of the turn table, and by moving the actuating lever 45 to reciprocate the saddle 33 slidably mounted for transverse movement upon the slide. Movement of slide 25 enables the operator to bring the desired portion of the article being treated into alignment with the wheel W, while reciprocation of the saddle 33 enables the same to be brought into contact or removed from the wheel. Besides these rectilinear movements, due to the pivotal mounting of the turn table upon the pedestal, both the slide 25 and the saddle 33 carried thereby may be rotated about the shaft 15 as an axis by merely shifting the angular position of the parts by moving the hand wheel 30 from side to side. Such rotative movement is particularly desirable in polishing curved or irregular articles, and by suitably combining this rotative movement with the rectilinear movements above described the entire surface of an article may be thoroughly and uniformly treated regardless of its shape. This feature of operation is particularly effective due to the fact that the axis of rotation of the turn table is disposed in the same vertical plane as the polishing wheel, as previously pointed out and as clearly shown in Figs. 2 and 6. It is again noted that the rotary movement of the turn table and the reciprocating movement of slide 25 is accomplished by the operator grasping but a single actuating element, and that either movement, as well as the movement of the saddle 33, is at all times responsive to the

touch of the operator, and entirely independent of mechanical devices tending to render the machine less sensitive thereto.

In case the articles to be treated are cylindrical in form or have straight portions only to be presented to the wheel W, in which case it is unnecessary to rotate the turn table, the turn table may be locked against rotation by tightening the clamping collar 18. The work under such setting will then be brought into contact with the wheel by moving the saddle transversely of the slide, and its various parts presented to the wheel by reciprocating the slide by means of the hand wheel 30.

In case tapered articles of conical or frusto-conical form are to be polished, the housing 34 may be angularly adjusted by means of bolts 42 and arcuate slots 43 to dispose the spindle 72 at such an angle that the tapered surface is disposed parallel to the axis of the slide 25 and of the polishing wheel, after which it is merely necessary to reciprocate the parts in the manner set forth above in connection with the treatment of cylindrical articles.

In many machines of this character, whenever it is necessary to change mandrels on the work holding spindle, difficulty is experienced in unscrewing and replacing the same due to the free turning of the spindle. This difficulty is obviated in the present invention due to the engagement of lug 83 with the ends of the flange 91 when the clutch is sufficiently shifted towards the right, as viewed in Fig. 2.

It is thus seen that the invention provides an apparatus adapted to treat articles of various shapes and sizes, which is simple and compact in construction, effective in operation, in which the main carriage or slide is reciprocated by the same means as are employed by the operative to rotate the turn table, and in which the several movements of the various parts and the pressure exerted between the article treated and the buffing wheel are constantly responsive to the touch of the operator whereby to render the apparatus highly sensitive.

While but a single embodiment has been illustrated and described, it is obvious that changes may be made in the exact construction of the several parts without departing from the spirit of the invention, and it is, therefore, not intended to limit the invention beyond that specifically pointed out in the appended claims.

I claim:

1. A polishing machine comprising a pedestal, a turn table journaled in said pedestal, a carriage or slide mounted for reciprocating movement on the turn table, a saddle on the slide adapted to reciprocate in a plane at an angle to that in which the slide reciprocates, a housing carried by the saddle

and angularly adjustable thereon, and a work holding spindle journaled in said housing.

2. A polishing machine comprising a pedestal, a split clamping ring anchored to the pedestal adjacent its upper end, a turn table rotatably mounted on the pedestal, a boss depending from the turn table and projecting into the said clamping ring, means for moving said ring into gripping relation with the said boss, a reciprocating slide carried by the turn table, a single means for rotating the turn table and reciprocating the slide, a saddle slidably mounted on the slide for movement transverse to the axis of the slide, a gear housing carried by the saddle, a spindle journaled in said housing, gearing mounted therein for driving said spindle, a clutch member feathered on the said spindle for engaging and disengaging the driving gear and spindle, and means for preventing rotary movement of said clutch member when in disengaged position.
- 5 3. A polishing machine comprising a pedestal, a turn table journaled in said spindle, a slide mounted for reciprocating movement on the turn table, a rock shaft carried by said slide, a ratchet fixed to said shaft, an arm also fixed to said shaft, a reciprocating saddle mounted on said slide, a link having its opposite ends pivotally connected to said saddle and arm, an operating lever loosely mounted for rocking movement upon said shaft, and means carried by said lever for selectively locking the lever to the said ratchet.

4. A polishing machine comprising a pedestal, means for adjustably supporting the pedestal, a turn table journaled on the pedestal, a reciprocating slide mounted on the pedestal, a single means for rotating the turn table and reciprocating the slide, a saddle slidably mounted for movement in an angular direction to the reciprocating movement of the slide, means constantly under the influence of pressure exerted by the operative for reciprocating the said saddle, a gear housing carried by said saddle and angularly adjustable thereon, and a work holding spindle journaled in said housing.
- 45 5. A polishing machine comprising a ped-

estal, a turn table rotatably mounted on the pedestal, a reciprocating slide carried by the turn table, a single means for rotating the turn table and reciprocating the slide, a saddle slidably mounted on the slide for movement transverse to the axis of the slide, a gear housing carried by the saddle, a spindle journaled in said housing, gearing mounted therein for driving said spindle, a clutch member feathered on the said spindle for engaging and disengaging the driving gear and spindle, and means for preventing 50 55 60 rotary movement of said clutch member when in disengaged position.

6. A polishing machine comprising a pedestal, spaced bearings in said pedestal, a shaft provided with a turn table at its upper end journaled in said bearings, said turn table having a guiding rib formed thereon, a reciprocating slide mounted for sliding movement on said rib, a second guiding rib formed on the upper surface of the slide and extending at substantially right angles to the axis of the slide, a saddle mounted for sliding movement on said second named rib, a gear housing carried by and angularly adjustable upon the saddle, a work holding spindle journaled in said housing, gearing within the housing for rotating the spindle and a clutch also within the housing for engaging and disengaging the gearing and spindle.

7. A polishing machine comprising a pedestal, a turn table journaled therein, a reciprocating slide mounted on the turn table, a saddle slidably mounted on the slide for movement transverse to that of the slide, a work holding spindle carried by said saddle, means adapted to support a backing block carried by the saddle and spaced from the inner end of said spindle whereby an article held between said spindle end and backing block may be centered over the vertical axis of the turn table and adjusted to varying distances therefrom.

In testimony whereof, I sign my name.

ROBERT FLOYD SALISBURY.
